UNITED STATES PATENT OFFICE.

FRIEDRICH GRAFFENBERGER, OF MILWAUKEE, WISCONSIN, ASSIGNOR TO A. GEO. SCHULZ CO., OF MILWAUKEE, WISCONSIN, A CORPORATION OF WISCONSIN.

SAFETY DEVICE FOR PRESSES.

1,138,374.

Specification of Letters Patent.

Patented May 4, 1915.

Application filed June 20, 1914. Serial No. 846,240.

To all whom it may concern:

Be it known that I, FRIEDRICH GRAFFENBERGER, a citizen of the United States, residing at Milwaukee, in the county of Milwaukee and State of Wisconsin, have invented certain new and useful Improvements in Safety Devices for Presses and the like, of which the following is a specification, reference being had to the accompanying drawing, forming a part thereof.

This invention relates to presses or similar machines in which the work is pressed or acted upon by dies one of which is movable toward and from the other. It is shown for the purpose of illustration in connection with a corner staying machine for applying gummed stays or strips to the corners of pasteboard or paper boxes, although it is applicable to machines having reciprocating tools or parts for performing other operations.

The main objects of the invention are to prevent crushing or injuring the fingers of operatives employed in feeding such machines and to avoid mutilating and spoiling work improperly placed between the dies or presented to the tools without interfering with the rapid and most efficient operation of the machines.

It consists in the construction, arrangement and combination of parts as herein-after particularly described and pointed out in the claims.

In the accompanying drawing like characters designate the same parts in the several figures.

Figure 1 is a side elevation and vertical section on the line 1—1, Fig. 2, of a portion of a corner staying machine embodying the invention; Fig. 2 is a front elevation thereof; Fig. 3 is a front elevation and longitudinal section of the pitman on the line 3—3, Fig. 1, showing the parts of the pitman in normal working condition; Fig. 4 is a front elevation similar to Fig. 2, showing the parts in different positions; and Fig. 5 is a front elevation and section similar to Fig. 3, showing the parts of the pitman in the positions they assume when the movable die or guard encounters an obstruction.

The staying machine in connection with which the safety devices constituting the present invention are shown, comprises a

vertically reciprocating head 1, guided between parallel ways 2, a die 3, adjustably and detachably connected with the lower end of the head, an anvil or stationary die 4, adjustably and detachably connected with the frame of the machine below the die 3 and a crank or eccentric 5, mounted on the front end of a horizontal shaft 6, which is supported in bearings in the upper part of the machine frame, and has a suitable clutch controlled driving connection (not shown).

The head 1 has a longitudinally movable block 7, fitted and guided in a recess in the rear side of the head and provided with a rearwardly projecting wrist pin 8. A cylindrical stem 9, having an adjustable threaded connection with the upper end of the block 7, extends upwardly therefrom and is guided in bearings formed therefor in the head 1. At its upper end the stem 9 is formed with a squared wrench head 10. In a recess formed in the head 1 between the bearings of the stem 9 and covered by a removable plate 11, a strong spiral spring 12 encircles the stem, bearing at its lower end against the head and at its upper end against a washer 13, which is seated against a shoulder formed on the stem by the enlargement of its upper end. The movable die 3, which is rigidly secured to the lower end of the head 1, is thus permitted to yield upwardly with the head when it is forced by the eccentric 5 downwardly upon work held on the anvil or stationary die 4, in applying gummed stay strips to the corners of boxes. The stem 9 affords means for adjusting the die 3 vertically relative to its driving connection and the anvil 4 to vary the pressure and properly operate on stock of different kinds and thicknesses. A knife or cutter 14, fastened to the frame of the machine at the rear end of the die 3 above the anvil 4, is formed with an inverted V-shaped cutting edge corresponding with the die and anvil for coöperating with the die to sever the stay strip, which is fed by means not shown, over a guide 15 through an opening in the knife between the die and anvil when they are separated, as shown in Figs. 1 and 2. The die 3 is secured in place in a socket in the head 1 by a screw 16, which serves also to adjust the rear end

of the die so that it will work properly with the knife 14.

As thus far described the machine is of well known construction and no claim is made thereto *per se*.

For actuating the head 1 with the die 3, the eccentric 5 is connected with the wrist pin 8 by a pitman 17, and to prevent crushing and injuring the fingers of operatives and to avoid mutilating and spoiling work misplaced on the anvil 4, the pitman has a yielding connection with one of the parts connected thereby, and is preferably constructed as follows, and as shown in detail in Figs. 1, 3 and 5. At its lower end it is formed with a head or cylindrical bearing fitting the wrist pin 8, and at its upper end with a longitudinally slotted strap head fitting the upper side of the eccentric or crank pin 5. A bearing piece 18, fitting the lower side of the eccentric or crank pin 5, is fitted and guided in the slotted head and movable lengthwise of the pitman. The bearing piece 18 is formed or provided with a stem 19, preferably square, which is loosely fitted and guided in a longitudinal socket or hole formed therefor in the pitman. For convenience of construction, the socket or hole for the stem 19 preferably extends through the opposite end of the pitman. The bearing piece 18 is yielding held against the eccentric or crank pin 5 by a spring 20 inserted in the hole or socket of the pitman and bearing at one end against the inner end of the stem 19 and at the opposite end against a block 21 fitted to the wrist pin 8. On one side the stem 19 is cut away to form a notch or shoulder 22, and in a transverse opening in the pitman 17 a latch 23 is fitted and adapted when thrust inward to engage with the shoulder 22 and lock the bearing piece 18 in its normal working position in which it is shown in Fig. 3. A cam lever 24, fulcrumed at its lower end in a longitudinal groove or recess in one side of the pitman 17, projects at its upper end into an opening in the latch 23, in which it has a limited amount of play. A spring 25, held in a socket in the side of the pitman 17 and bearing at its outer end against the inner side of the lever 24, holds the latch normally in its retracted or inoperative position, as shown in Fig. 3, leaving the bearing piece 18 free to yield toward the wrist pin 8. On its outer side the lever 24 is formed with a projection 26, and in the path of this projection an adjustable abutment 27 is attached to the frame of the machine in position to thrust the latch 23 inward when the die 3 is within a certain distance of the anvil 4. This abutment 27 may be conveniently made in the form of an eccentric having a cylindrical stem passing through a transverse hole in one side of the frame and secured

in adjusted position therein by a nut 28 threaded on its outer end. By turning the stem, the eccentric head or abutment on its inner end is set in different positions for operating the latch 23 at different points in the downward or advance movement of the die 3. A spring 23' held in a socket in the latch, presses at its outer end against the lever 24, normally holding it against the outer side of the opening in the latch, as shown in Figs. 3 and 5. This loose yielding connection between the lever and latch compensates for variation in the throw of the lever due to change in the adjustment of the abutment 27, and permits any excess movement of the lever beyond that required to properly engage the latch with the shoulder 22 without causing the latch to bind on the stem 19, or subjecting the lever and connected parts to injurious strains. The pitman thus constructed constitutes a yielding connection between the eccentric or crank pin 5 and the wrist pin 8, and in connection with the latch 23, lever 24 and abutment 27, will, when properly adjusted, prevent crushing the fingers of operatives, but will not alone prevent bruising the fingers if they are caught between the die and anvil, or prevent mutilating and spoiling work improperly placed on the anvil, since the fingers or work under these conditions will be subjected to the weight and impact of the descending head 1 and pressure of the spring 20.

To prevent bruising or hurting the fingers of operatives and mutilating and spoiling work, the machine is further equipped with means for arresting the downward or advance movement of the die and the head to which it is attached, when an obstruction such as a finger of the operator, or improperly adjusted work, is placed in the path of the die in such position that it would be crushed or injured by its further advance. To this end the reciprocating head 1 is provided with a clutch or clutches for clamping or locking it to a stationary part or parts of the machine and with a guard or guards movably connected with the head and adapted when it meets an obstruction in its path, to operate the clutch or clutches and arrest further advance of the head and the die 3, the yielding connection of the pitman with the eccentric or crank pin 5 permitting the eccentric or crank pin to complete its revolution when the advance of the die 3 is thus arrested.

The clutching or locking device and the movable guard for operating the same, may be conveniently constructed and applied to a corner staying machine of the character shown, as follows: A plate or block 29, attached to the front side of the head 1, is formed in the ends overhanging the ways 2, with pockets 30, having upwardly and out-

wardly inclined walls, and in these pockets, 5 rollers 31 are loosely confined. To the ways 2, plates or abutments 32 are attached, having inclined projections 33 on their inner sides in the paths of the rollers 31 when the latter are lifted as hereinafter explained and as shown in Fig. 4, into the upper narrower portion of the pockets 30. L-shaped guards 34, which may be made of comparatively light sheet metal, are movably connected with the front face of the plate or block 29, and a similar plate or block 35, attached to the head 1 below and at a distance from the plate or block 29 by screws 36, threaded in said plates or blocks and passing loosely through vertical slots in the guards, the screws being provided next to their heads with washers, which are spaced from said plates or blocks and prevented from binding 20 against the guards by oblong washers 37, as shown in Fig. 4. At their lower ends the guards, which project inwardly toward each other, as shown in Figs. 2 and 4, are formed or provided as shown in Fig. 1, with rearwardly projecting arms 38, adjacent to and parallel with the die 3. The upwardly extending vertical members of the guards overlie the pockets 30 and confine the rollers 31 therein. A cross bar 39 is adjustably attached adjacent to its ends to the vertical members of the guards between the plates 29 and 35 by screws 40, threaded in said bar and passing through vertical slots in the guards. The guards are thus connected with each 35 other and made to operate as one. Light spiral springs 41, seated in sockets formed in the upper side of the bar 39, adjacent to its ends, pass upwardly and are loosely guided in vertical openings through the plate 29 into the lower ends of the pockets 30 and are adapted to elevate the rollers 31 in said 40 pockets when the downward movement of the guards is arrested by an obstruction.

In the operation of the machine equipped 45 with safety devices as hereinbefore described, the abutment 27 being adjusted to lock the yielding bearing piece 18 in its normal working position in which it is shown in Fig. 3 just before the die 3 in its downward movement comes into contact with a box corner held on the anvil 4, the further downward or 50 advance movement of the die positively presses a gummed stay which has been fed forward between the die and anvil and cut to the required length by the die and knife 14, against the box corner on the anvil. In 55 case the operator inadvertently thrusts a finger into the path of the descending die either from the front or side while the die is far enough above the anvil to admit of the insertion of a finger between them and before the 60 projection 26 on the lever 24 has descended far enough to encounter the abutment 27 and lock the bearing piece 18 in its normal working position in the pitman, the obstruction

thus presented to the descent of the guards 34 will shift them upwardly relative to the head 1, causing the springs 41 to lift or support the rollers 31 while the plate 29 with the pockets 30 descends and thrusts the rollers 70 outwardly into engagement with the projections 33 on the plates 32, as shown in Fig. 4. The head 1 is thus clutched or locked to the stationary ways 2 in which it is guided, and the further downward movement thereof 75 and of the die 3 is instantly arrested, preventing injury to the finger of the operator. The further downward or advance movement of the wrist pin 8 being thus arrested, the continued rotation of the eccentric or crank 80 pin 5 shifts the bearing piece 18 downward in the slotted strap head of the pitman, compressing the spring 20, as shown in Fig. 5. Upon the completion of the rotation of the eccentric or crank pin 5, the parts of the pitman and the head 1 with the die 3, are returned to their initial positions, as shown in 85 Figs. 1, 2 and 3. If a box is improperly placed on the anvil in such a position that it would be crushed or injured by the descent of 90 the die 3, as indicated at 42 in Fig. 4, it will by engagement with either one of the guards, operate the clutches and arrest the descent of the head 1 with the die 3, as above explained, and thereby prevent spoiling or mutilating the box. The spring 20, which is made of sufficient strength to overcome the 95 inertia of the head 1 and friction between it and the ways 2, prevents the shoulder 22 on the stem 19 from being shifted in the pitman 100 out of position for engagement with the latch 23 when the latter is thrust inwardly by the engagement of the projection 26 on lever 24 with the abutment 27, and thus enables the machine to be operated with greater 105 rapidity than would be possible without such a spring.

Various modifications in the details of construction and arrangement of parts may be made in the adaptation of the safety devices 110 to different machines for various kinds of work, without departure from the principle of the invention as defined in the following claims.

I claim:

1. In a press or the like having a reciprocating part and an eccentric for actuating said part the combination of a pitman connecting the eccentric with said reciprocating part and having a bearing guided and 120 movable in one end thereof toward and from the other end, a latch guided in the pitman transversely to its length and adapted to lock said bearing in its normal working position, a cam lever fulcrumed to and 125 extending lengthwise of the pitman and having a yielding connection with the latch, a spring tending to hold the latch out of operative position, and an abutment in the path of the cam lever adapted to thrust the 130

4
latch into operative position when said reciprocating part reaches a certain point in its advance movement.

2. In a press or the like having a reciprocating part and an eccentric for actuating said part the combination of a pitman connecting the eccentric with said reciprocating part and having at one end a bearing guided and movable lengthwise of the pitman, a 10 spring tending to hold said bearing in its normal working position in the pitman, a latch guided in the pitman transversely to its length and adapted to lock said bearing in its normal working position relative to 15 the pitman, a cam lever fulcrumed to and disposed lengthwise of the pitman and having a yielding connection with the latch, a spring tending to hold the latch out of operative position, and an adjustable abutment in the path of the cam lever adapted 20 by engagement therewith to thrust the latch into operative position at a predetermined point in the advance of said reciprocating part.
- 25 3. In a press or the like having a reciprocating part and an eccentric for actuating the same, the combination of a pitman connecting the eccentric with said reciprocating part and having a yielding bearing at one 30 end, means adapted to lock said bearing in its normal working position at a certain point in the advance movement of said reciprocating part, a guard movably connected with said reciprocating part, and 35 means operated by said guard to arrest the advance of said reciprocating part when the guard meets an obstruction.
4. In a press or the like having a reciprocating part and an eccentric for actuating 40 the same, the combination of a pitman connecting the eccentric with said reciprocating part and having a yielding bearing at one

end, a guard movably connected with said reciprocating part, and means operated by said guard to arrest the advance of said 45 reciprocating part when the guard meets an obstruction.

5. In a press or the like the combination with a reciprocating head and an eccentric for actuating the same, of a pitman connecting the eccentric with said head and having a longitudinally yielding connection with one of said parts, a clutch having a movable member carried by the head and adapted by engagement with a stationary part of the 50 machine to arrest the advance of the head, and a guard movably connected with the head and adapted when it meets an obstruction to shift the movable clutch member into operative position.

6. In a press or the like having a reciprocating head and an eccentric for actuating the same the combination of a pitman connecting the eccentric with said head and having a longitudinally yielding connection with one of the connected parts, a clutch comprising a pocket having a rearwardly and outwardly inclined wall carried by the head, a roller loosely confined in said pocket and a stationary abutment adjacent to the 65 path of the roller, a guard movably connected with the head and adapted to thrust said roller backward in its pocket against the inclined wall thereof into position to engage with said abutment and to arrest the 70 advance of the head when the guard meets an obstruction.

In witness whereof I hereto affix my signature in presence of two witnesses.

FRIEDRICH GRAFFENBERGER.
